UNITED STATES PATENT OFFICE.

MARTIN L. WILLIAMS, OF SOUTH BEND, INDIANA.

INTERNAL-COMBUSTION ENGINE.

1,027,680.

Specification of Letters Patent.

Patented May 28, 1912.

Application filed December 20, 1909. Serial No. 534,154.

To all whom it may concern:

Be it known that I, MARTIN L. WILLIAMS, a resident of South Bend, in the county of St. Joseph and State of Indiana, have invented certain new and useful Improvements in Internal-Combustion Engines, of which the following is a full, clear, and precise specification.

My invention relates to internal combustion engines, particularly to improved multi-cylinder two-cycle engines.

In prior engines of this class a compression cylinder is associated with each main cylinder to supply the main cylinder with explosive gas, such arrangement necessitating more or less valve mechanism. In these prior art engines a crank case is also provided and used as a reservoir or passageway for fluid flow from one cylinder to another.

Among the salient objects of my invention are to provide a construction in which the main cylinders are arranged in sets of two, one cylinder of each set being provided with auxiliary cylinder and piston mechanism for in common supplying both cylinders of each set with explosive gas; to provide a simplified and very efficient construction and arrangement of such auxiliary cylinder and piston mechanism that the weight and size of the cylinder part of the engine

will be reduced to a minimum; more in detail to provide a construction in which the auxiliary cylinder of each set is arranged concentrically with the main cylinder of the set, the auxiliary piston forming an extension on the main piston for said cylinder and the auxiliary piston part dividing the auxiliary cylinder into upper and lower compression compartments in which are

compressed supplies of gas, the supply from one compartment being for the one cylinder of the set and the supply from the other compartment being for the other cylinder of the set; to provide an arrangement which will eliminate all movable valve mechanism and which involves only ports controlled by the pistons and the auxiliary piston of each set; to provide a construction and arrangement which will cause the gas supplies to be first put under compression and then practically instantaneously charged into the cylinders in the proper sequence; to provide mechanical construction which will enable the main cylinders and the greater part of the auxiliary cylinders to be cast in one piece; and to provide an arrangement of the

main cylinders and auxiliary mechanism which will enable the crank case to be entirely dispensed with, this greatly reducing the weight, size and cost of the engine, and furthermore leaving one end of the cylinder entirely open to the external air to greatly facilitate cooling. The engine of my improved construction can, therefore, be made very light and small yet with great power and efficiency, making it particularly adaptable in the air-ship field where these elements are essential. The cylindrical, concentric arrangement of the various cylinder parts of my engine greatly reduces the labor and cost of machining, thus greatly reducing the cost of manufacture.

The various features, construction and arrangement of my improved engine are clearly described in the following specification and shown on the accompanying drawings.

In these drawings Figure 1 is a plan view of the engine, Fig. 2 is a sectional view taken on plane 2—2, Fig. 1, Fig. 3 is a sectional view of the lower end of adjacent auxiliary cylinders showing the position of the gas intake ports, Fig. 4 is a sectional view taken on plane 4—4, Fig. 2, and Fig. 5 is a sectional view taken on plane 5—5, Fig. 2.

The engine comprises driving sections A, B, C, and D. The section A comprises a cylinder part 1 closed at its upper end by a head 2 and open at its lower end, a hollow piston 3 being adapted for reciprocation in the cylinder. Supported diametrically within the piston is a shaft 4 pivoting the head of a connecting rod 5 whose outer end pivots to the crank section 6 of the crank shaft 7. The section D has a construction exactly similar to that of section A and comprises cylinder 1' having the head 2', piston 3', shaft 4' and connecting rod 5', the connecting rod engaging crank section 6' on the crank shaft, which section is displaced ninety degrees from the crank section 6. Section B comprises the cylinder 8 closed at its top by the head 9 and accommodating a hollow piston 10 whose lower end 11 forms the inner wall of a hollow annular auxiliary piston 12. From the lower edge of the wall of cylinder 8 extends the annular flange 13 forming the top wall of an annular auxiliary cylinder compartment 14 in which the auxiliary annular piston 12 reciprocates, the outer wall of this annular compartment be-

ing provided by the cylindrical shell 15 depending from the outer edge of the flange 13. The inner wall of the annular cylinder is formed partly by the cylindrical shell 16 5 extending upwardly into the hollow piston 10 and partly by the intermediate section 17 of the main piston. The lower wall of the annular cylinder is formed by the flange 18 extending from the lower end of the part 10 16 into engagement with the lower end of the cylindrical outer shell 15. Within the piston 10 is carried the shaft 19 pivoting the head of the connecting rod 20 which at its outer end pivots to the crank section 21 displaced one hundred eighty degrees from the section 6 and ninety degrees from the crank section 6'.

The driving section C is exactly similar to the section B and comprises the same 20 parts whose reference characters are primed, the connecting rod 20' pivoting to crank section 21' displaced ninety degrees from crank section 21 and one hundred eighty degrees from crank section 6'. I preferably cast in 25 a single piece 22 the main cylinders and the outer walls of the auxiliary cylinders, the auxiliary cylinder walls of the sections B and C merging at their inner parts and at 30 their outer parts merging with the cylinders 35 of sections A and D, as shown. The shells 16 and 16' are preferably cast integral with their flanges 18 and 18', as shown. All the cylinder parts are, therefore, cylindrical and concentrically arranged so that the cost of 40 machining is reduced to a minimum. The crank shaft 7 is journaled in bearing extensions 23 secured at suitable intervals to the main casting 22. Each cylinder is provided with a spark plug P secured to the 45 head to project its spark terminals p into the main cylinder. The upper end of each piston has a central inlet opening 24 communicating with radial ports 25 extending through and terminating at the periphery 50 of the piston just within the upper end of the piston. In the wall of each cylinder there is also provided an annular port 26 having radial branches 27 communicating with the cylinder compartment in a horizontal plane, these annular ports each communicating with a common exhaust pipe 28.

The port outlets of each cylinder are in a horizontal plane to be closed by the piston during the greater part of its movement and 55 to be exposed just before the piston reaches the lower end of its movement to be again closed when the piston begins its upward movement. In Fig. 2 these port outlets are closed by the pistons in sections A, B and D 60 and are exposed in the section C. Just below the plane of the exhaust outlets 27 the cylinder walls of the sections A and D have annular inlet ports 29 having radial branches 30 communicating with the cylinder compartment, the outlets being in a plane to

register with the radial ports 25 communicating with the central piston opening 24 when the piston is in its lowermost position. The annular passageway 29 of the section A communicates with passageway 31 which 70 leads into the upper compartment 14^a of the annular auxiliary cylinder 14, and the annular passageway 29 of section D communicates with a similar passageway 31' which 75 leads into the upper compartment 14'^a of the auxiliary cylinder 14' of section C.

As best shown in Figs. 1 and 4, the outer wall of the auxiliary cylinder of section B is provided with enlargements 32 having internal passageways 33 which extend radially 80 over the top wall 13 to communicate with the radial ports 25 leading to central opening 24 of the piston of section B when the piston is in its lowermost position. The passageways 33 communicate with the lower 85 end of the lower compartment 14^b of the auxiliary cylinder 14. Likewise enlargements 32' on the outer wall of cylinder 14' of section C provide passageways 33' for connecting the lower end of the compartment 14'^b with the central opening 24 of the corresponding piston when said piston is in its lowermost position, as shown.

Referring to Figs. 1 and 3, a flanged lug 34 extends from the main frame 22 to be 95 connected with a source of gas supply and having the branch passageways 35 and 35' terminating in the auxiliary cylinders 14 and 14' in a middle plane thereof, the auxiliary pistons being of such height as to 100 expose the respective gas inlets when the auxiliary pistons reach the upper and lower ends of their reciprocations.

The operation of the engine can now be readily understood. As shown in Fig. 2, 105 the pistons of sections A and B are at half stroke, the piston of section C is at the lower end of its stroke, and the piston of section D is at the upper end of its stroke. In section B the auxiliary piston is moving downwardly to compress a supply of gas in lower section 14^b of the auxiliary cylinder, which supply was drawn in during the last up stroke of the piston, and the piston is drawing vacuum in the upper compartment 14^a 110 which is dis-connected from cylinder 1 as piston 3 is in a position to close the passageway 31. Piston 10 closes the outlet to cylinder 8 from passageway 33, and the compressed gas in compartment 14^b will not enter cylinder 8 until the piston reaches the lower part of its stroke to bring ports 25 into register with the passageways 33, as 115 illustrated in section C. As soon as these ports register the compressed gas will flow 120 outwardly through central opening 24, and being under heavy compression, will flow in a solid stream centrally through the cylinder against the top thereof. When the piston is down the exhaust openings 19 of 125

cylinder 10 will also be exposed, and the exhaust gas will flow down along the sides of the cylinder and out through the exhaust ports and to exhaust pipe 28. Gas charge to cylinder 9, therefore, takes place substantially instantaneously. When the piston reaches the lower end of its stroke the top of the auxiliary piston will have cleared gas inlet 35 for the upper compartment 14^a, and a charge of gas will be almost instantaneously sucked into compartment 14^a by the vacuum effect created therein by the descent of the auxiliary piston.

When the piston 10 begins its up stroke intake ports 33 are closed by the piston and the gas previously charged in cylinder 8 is put under compression until the piston reaches the end of its up stroke. When piston 10 traveled downwardly piston 3 traveled up and compressed in its cylinder a previous charge of gas which was exploded to force the piston 3 downwardly, and the piston will reach the lower end of its stroke when piston 10 reaches the upper end of its stroke, and at this time the intake ports 25 of piston 3 will register with the ports 27 so that the compressed supply of gas in compartment 14^a of the auxiliary cylinder will be forced instantaneously into cylinder 2 through the central opening of piston 3, the exhaust gases flowing at the same time from said cylinder through the exhaust ports into the exhaust pipe, whereupon piston 3 will again move upwardly to compress the received charge. When piston 10 reached the upper end of its stroke the auxiliary piston had exposed the gas inlet 35 to lower compartment 14^b, and the vacuum effect created in this lower compartment upon the up stroke of the auxiliary piston drew in a supply of gas. Now when piston 10 again moves downwardly after explosion of the charged gas in cylinder 8 the gas supply in the lower compartment will be compressed and vacuum will again be drawn in the upper compartment 14^a, the compressed supply in the lower compartment being forced into the cylinder 8 when piston 10 again reaches the lower end of its stroke, and the various cycles traced are repeated. Thus a single auxiliary mechanism associated with section B serves to control the charging for both cylinders of the set, the upper auxiliary compartment receiving and compressing the charge for cylinder 1 and the lower auxiliary compartment receiving and compressing the charge for cylinder 8. Sections C and D coöperate in the same manner as sections A and B, one auxiliary cylinder mechanism sufficing for the two main cylinders of the set, the upper auxiliary compartment receiving and compressing the charges for cylinder 1', and the lower auxiliary compartment receiving and compressing the charges for main cylinder 8'. Two auxiliary cylin-

der mechanisms, therefore, control the charging for four main cylinders, whereas in prior engines it required one auxiliary cylinder mechanism for each main cylinder. The unique way of encircling the two inner main cylinders by the auxiliary cylinders requires practically no additional space, a great many walls acting in common for the auxiliary and main cylinder parts. Furthermore, no valve mechanisms are necessary, as the flow between any points can be controlled by the movable pistons in conjunction with port passageways. The auxiliary pistons besides acting in their compression capacity serve also to accurately guide the main pistons of which they form a part. Also by intimately associating the auxiliary and main cylinders more or less complicated cross connecting members are eliminated which would be necessary were the auxiliary cylinders independent of the main cylinders. As a result of my arrangement, therefore, there will be no movable parts except the piston frames, and a very compact, small and light, yet powerful and efficient engine results which is particularly adaptable for application in the air-ship field or in other fields where the above features are requisites. The cost of production is also very much reduced owing to the small number of castings and owing to the cylindrical and concentric arrangement of the parts, which enables machining and finishing to be easily and quickly obtained. The central intake inlet in the piston heads will cause the intaken gas to be directed in a solid axial stream to the top of the cylinder to in no wise interfere with the exhaust gases escaping from the bottom of the cylinder at the sides thereof, the intaken gas, in fact, assisting in driving out the exhaust gases.

As in my construction it is not necessary to utilize the crank case as a storage chamber or passageway for inter-communicating gases, the crank case can be entirely omitted and only skeleton supporting frames provided on the main frame for journaling the crank shaft. This enables me to leave the interior of the cylinders entirely exposed to the atmosphere, which greatly assists in keeping the engine cool and clean. The engine nowhere has heavy metallic parts, all the parts being in the form of thin walls having large external radiating areas. The result is that special cooling means such as water jackets can in most cases be dispensed with, this also enabling the engine to have much less weight and size than prior engines. The very small number of parts also reduces lost motion and noise to a minimum. The engine is at all times properly cushioned and balanced and will run smoothly. The flow of gases from one part to another of the engine is not sluggish, but flow from one part to the other takes place practically in-

stantaneously. Each cylinder operates on the two cycle principle, there being one explosion for each complete reciprocation of the piston. Any number of cylinder sets 5 can be provided to build up a multiple cylinder engine of any capacity, one cylinder for each set controlling in common the intake for both cylinders.

Changes could, of course be made in the 10 detail construction and arrangement without departing from the scope of my invention, and I do not therefore, wish to be limited to the disclosures herein, but

I desire to secure the following claims by 15 Letters Patent:

1. In a gas engine, the combination of two main cylinders, a piston for each cylinder, an auxiliary cylinder concentric with one of said main cylinders, an inlet to the auxiliary cylinder for gas, connections between said auxiliary cylinder and the main cylinders, and a piston for said auxiliary cylinder carried by the piston of the corresponding main cylinder and operable in the auxiliary cylinder to control the charging of gas 20 from the auxiliary cylinder to both main cylinders.

2. In a gas engine, the combination of two main cylinders each provided with a piston, 25 an annular auxiliary cylinder concentric with one of said main cylinders, an annular piston for said auxiliary cylinder forming part of the corresponding main cylinder piston, an inlet to said auxiliary cylinder for 30 gas, and connections between said auxiliary cylinder and the main cylinders, said auxiliary cylinder and piston coöperating to alternately charge gas from the auxiliary cylinder to the main cylinders.

3. In a gas engine, the combination of two main cylinders each having a piston, an outer wall concentric with one of said main cylinders, an inner stationary wall, said outer wall forming the outer boundary of 40 an auxiliary annular cylinder and said stationary inner frame forming part of the inner boundary of said auxiliary cylinder, the main piston of the corresponding main cylinder forming the remaining part of the inner boundary of said auxiliary cylinder, a wall extending between said main cylinders and the outer wall to form the upper boundary of said auxiliary cylinder, a wall extending from said inner stationary frame to 45 said outer wall to form the lower boundary of said auxiliary cylinder, an auxiliary piston formed at the lower end of said main piston and adapted to reciprocate therewith and in said auxiliary cylinder, an

inlet to said auxiliary cylinder for gas, and 50 connections between said auxiliary cylinder and the main cylinders, said auxiliary piston coöperating with the auxiliary cylinder upon reciprocation of the corresponding main piston to in common control the charg- 55

ing of gas from the auxiliary cylinder to the main cylinders.

4. In a gas engine, the combination of a cylinder frame having an inner section of one diameter and an outer section of greater 70 diameter, a piston for reciprocating in said inner section, an annular flange extending downwardly from the piston, an annular wall extending inwardly a distance from the outlet of said outer section and connected at its outer end with said outer section, said annular wall also extending into the piston flange, said outer cylinder section, said annular wall and said piston forming an annular auxiliary cylinder compartment, the outer end of said piston flange expanding to 75 form a piston for said auxiliary cylinder compartment, an inlet to said auxiliary cylinder compartment for gas, and connections between said auxiliary cylinder compartment and the compartment within the inner cylinder section, said auxiliary cylinder compartment traveling with said main piston to control the charging of gas from said auxiliary cylinder compartment to the inner 80 cylinder section compartment.

5. In a gas engine, the combination of a main cylinder and a piston therefor, an auxiliary cylinder and piston therefor, said main cylinder piston having an axial port 95 and a passageway extending from said port and terminating at the periphery of said main cylinder, a passageway leading from said auxiliary cylinder and terminating at the inner surface of the main cylinder to be 100 in register with the passageway leading from the axial port in the main piston when the main piston is in its out position whereby said axial inlet port will be out of connection with said auxiliary cylinder until 105 said main piston reaches its out position, said auxiliary cylinder having a gas intake port positioned to be cleared by the auxiliary piston to feed gas into said auxiliary cylinder when the auxiliary piston is in its 110 inner position, said pistons moving outwardly simultaneously whereby the fed-in gas compressed in the auxiliary cylinder by the outwardly moving auxiliary piston will be compressed and discharged into the 115 main cylinder under heavy pressure when the main piston reaches its outer position, and exhaust outlet from said main cylinder positioned to be opened when the main piston reaches its out position, the charged gas 120 flowing into the main cylinder in an axial column, the exhaust gases flowing along the sides of the main cylinder and through the exhaust outlet.

6. In a gas engine, the combination of a main cylinder and an auxiliary cylinder concentric therewith, an integral piston structure forming a piston for the main cylinder and a piston for the auxiliary cylinder, a gas inlet for the auxiliary cylinder positioned 125 130

to be open to supply gas to the auxiliary cylinder when the auxiliary piston is in its innermost position and to be closed while the auxiliary piston is moving toward its outermost position, said main piston having an axial port and a lateral passageway terminating at the periphery of the main piston, a passageway leading from the auxiliary piston and terminating at the inner surface 5 of the main cylinder to be in register with the lateral passageway of the main piston when the piston structure is in its out position and to be closed to the main cylinder until the piston structure reaches the 10 out position whereby the gas fed to the auxiliary cylinder and compressed therein by the outwardly moving auxiliary piston will be charged under heavy pressure into the main cylinder when the main piston reaches the out position, and exhaust outlet 15 from the main cylinder in position to be opened only when the main piston reaches the out position, the charged in gas flowing in an axial column through the main cylinder, and the exhaust gases flowing along the sides of the main cylinder and through the exhaust outlet.

7. In a gas engine, the combination of one cylinder having a piston, a second cylinder 20 having a piston, a gas inlet to the second cylinder positioned to be open when the piston for said second cylinder reaches one end of its stroke and to be closed while said piston travels to the other end of its stroke, said piston for the first mentioned cylinder 25 having an inlet passageway, there being a passageway from said second mentioned cylinder and terminating at said first mentioned cylinder to register with the passageway of the piston of said first mentioned cylinder when said piston is in its out position, the gas received in said second mentioned cylinder when the piston for said cylinder is

at one end of its stroke being compressed by said piston when moving toward the other end of its stroke and fed under heavy pressure into the first mentioned cylinder when the piston for said first mentioned cylinder is in its out position, and said piston for the second mentioned cylinder creating a vacuum in said second mentioned cylinder upon return of its piston so that when the gas inlet port is again cleared said second mentioned cylinder will receive a substantially instantaneous charge of gas, and exhaust outlet from said first mentioned cylinder to open simultaneously with the connection of said cylinder with the second mentioned cylinder.

8. In a gas engine, the combination of two main cylinders each having a piston, an auxiliary cylinder having a piston and divided by said piston into upper and lower compartments, one of said main cylinders being connected with said upper compartment and the other main cylinder being connected with the lower compartment, valve mechanisms controlling said connections, and a common gas inlet for said auxiliary cylinder closed during the greater part of its reciprocation and open only when the auxiliary piston reaches the end of its strokes, the moving auxiliary piston thereby creating vacuum in one compartment and compression in the other compartment, and the vacuum compartment being instantly filled with fresh gas when the auxiliary piston reaches the end of a stroke.

In witness hereof, I hereunto subscribe my name this 17th day of December, A. D., 1909.

MARTIN L. WILLIAMS.
